(57) **CLAIM**

The ornamental design for the card wallet with phone stand, as shown and described.

DESCRIPTION

FIG. 1 is a front, right, and top perspective view of the card wallet with phone stand showing my new design;
FIG. 2 is a rear, left, and bottom perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof;
FIG. 8 is a bottom plan view thereof;
FIG. 9 is a second front, right, and top perspective view thereof but shown in an alternate position, where the card wallet with phone stand is in a folded state;
FIG. 10 is a third front, right, and top perspective view thereof but shown in an alternate position, where an unclaimed phone is placed on the phone stand;
FIG. 11 is a second rear, left, and bottom perspective view thereof but shown in an alternate position, where an unclaimed phone is placed on the phone stand;
FIG. 12 is a third rear, left, and bottom perspective view thereof but shown in an alternate position, where an unclaimed phone is placed on the phone stand; and,
FIG. 13 is a front, left, and bottom perspective view thereof, where an unclaimed phone is placed on the phone stand and the unclaimed cards are pulled out from the card wallet.
The broken lines in the drawings depict portions of the card wallet with phone stand that form no part of the claimed design. Additional broken lines showing of the phone and cards, in FIGS. 10-13, illustrate environmental structures that form no part of the claimed design.

1 Claim, 13 Drawing Sheets
